CLAIM

The ornamental design for an airboat transmission housing, as shown and described.

DESCRIPTION

FIG. 1 is a left, rear perspective view of the airboat transmission housing showing my new design; FIG. 2 is a bottom plan view thereof; FIG. 3 is a rear elevation view thereof; FIG. 4 is a top plan view thereof; FIG. 5 is a left perspective view thereof; FIG. 6 is a right perspective view thereof; FIG. 7 is a front interior view thereof; FIG. 8 is a left, rear perspective view of an alternate embodiment of an airboat transmission housing; FIG. 9 is a bottom plan view of the embodiment of FIG. 8; FIG. 10 is a rear elevation view of the embodiment of FIG. 8; FIG. 11 is a top plan view of the embodiment of FIG. 8; FIG. 12 is a left perspective view of the embodiment of FIG. 8;

FIG. 13 is a right perspective view of the embodiment of FIG. 8; and,

FIG. 14 is a front interior view of the embodiment of FIG. 8.

The broken lines shown in FIGS. 1 and 8 are illustrative of environment structure only and form no part of the claimed design.
